Primary Examiner — Nathan M Johnston(74) *Attorney, Agent, or Firm* — Pauly, DeVries Smith & Deffner LLC(57) **CLAIM**

The ornamental design for a corner shelf, as shown and described.

DESCRIPTION

FIG. 1 is a top perspective view of a corner shelf.

FIG. 2 is a front view of the corner shelf of FIG. 1.

FIG. 3 is a right side view of the corner shelf of FIG. 1.

FIG. 4 is a rear view of the corner shelf of FIG. 1.

FIG. 5 is a left side view of the corner shelf of FIG. 1.

FIG. 6 is a top view of the corner shelf of FIG. 1; and,

FIG. 7 is a bottom view of the corner shelf of FIG. 1.

The broken lines in the drawings illustrate portions of the corner shelf that form no part of the claim.

The labels used herein to describe orientation (e.g. front, rear, left, right) are merely for reference and are not intended to limit the interpretation of the design.

1 Claim, 7 Drawing Sheets(56)
